UNITED STATES PATENT OFFICE.

EDWARD J. BAKER, OF CHICAGO, ILLINOIS.

ADVERTISING DEVICE.

1,350,054.

Specification of Letters Patent. Patented Aug. 17, 1920.

Application filed April 22, 1918. Serial No. 230,150.

To all whom it may concern:

Be it known that I, EDWARD J. BAKER, a citizen of the United States, residing at Chicago, in the county of Cook and State of Illinois, have invented certain new and useful Improvements in Advertising Devices, of which the following is a specification.

This invention relates to the class of illuminated advertising display devices in which both moving and stationary objects are shown, and comprises certain novel features in the construction, arrangement and operation of the different parts as will be hereinafter set forth in detail.

15 The principal object of this invention is to provide a device of this character that is more especially adapted for use in places of amusement and in show-windows for display purposes.

20 Figure 1 is a front elevation showing a glass face and frame holding the same.

Fig. 2 is a similar view, the glass and frame being removed.

25 Fig. 3 is a vertical section on line 3, Fig. 2. A represents the front face or field which may be of glass or other transparent surface on which the display features are shown or reflected. The glass front is held in a frame B to which a back casing C is 30 removably secured and which provides a chamber receptacle 4 in which the actuating mechanism for producing the different effects is located.

35 An electric motor 5 transmits the necessary power and motion to the operating mechanism. The motor shaft 6 has a worm-gear *a* mounted on the outer end thereof which is in engagement with a gear-wheel 7 mounted on a compound crank-shaft 8, as 40 shown in Figs. 2 and 3. The crank-shaft 8 is provided with proper bearings in the removable back 9 of the casing C and a partition 10 in chamber 4. One end of the connecting rod 11 is mounted on a crank 12 formed on shaft 8; the opposite end of which has a pivotal connection 13 with a movement lever 14, at a point between its respective ends, as best shown in Fig. 2. The upper end of lever 14 has a pivotal bearing 15 in the partition 10. The opposite end of lever 14 is provided with a slot 16 for the loose engagement of the stem end 17 of a lamp-socket 18 carrying an incandescent lamp 19. The stem end of the lamp-socket extends through an elongated slot 55 opening 20 in partition 10 in reaching its

connection with the slot 16 in lever 14. By this arrangement of mechanism the lamp 19 is caused to move up and down in slot 20 and in this instance is intended to represent the sun of the solar system in the landscape scenery picture shown in Fig. 1. It is obvious that the mechanism may be varied to shorten or lengthen the path of the lamp in producing different effects in changing 60 the lights and shadows in the simulated landscape field illustrated. The lamp may be made to disappear behind the mountains 21 and then reappear at predetermined intervals in accordance with the effect to be produced.

65 The waterfall effect is produced by an endless display belt which runs over the three upper rollers 23, 24 and 25 and the lower roller 26. The upper rollers are 70 mounted on shafts 27, 28 and 29 respectively, and which are in turn provided with journal bearings in brackets 30 secured to the partition 10. The lower roller 26 is mounted on a shaft 31 provided with bearings in companion brackets 32 secured to the bottom of the casing C. The traveling belt 22, providing the waterfall feature will have painted or otherwise indicated thereon the simulation of a waterfall which 75 will produce the desired effect. Motion is transmitted to the waterfall feature by a driving belt 33 running over pulleys 34 and 35.

80 A cloud effect is provided for in the upper part of the frames and consists of a roller 36, the relative position of which is shown in Fig. 3 and indicated by dotted lines in Fig. 2. This roller will usually be 85 of glass and motion is transmitted thereto from the driving shaft 8 by a belt 37 which runs over pulleys 38 and 39 and a guide pulley 40. This roller will have indicated on its surface a changing cloud or sky effect which will be reflected on the transparent front or surface A, by a concave-convex reflector 41 located back of the roller. This roller will turn at a slow speed ordinarily but the speed may be varied in producing different effects. The relative position of the reflector 41 may change which 90 will also assist in producing changing effects.

95 Wavy lights and shadow effects are produced by a reflector-plate 42 having a pivot 100 connection 43 with partition 10 and free at the front edge as shown in Fig. 3 and in

dotted lines in Fig. 2. The upper surface of this plate may be of any suitable color preferably red in giving a fleeting cloud effect. This plate is capable of a rocking movement on its pivot and is actuated by a rod 44 having a pivot connection therewith as at 3. The other end of rod 44 has a proper working connection with the crank driving-shaft 8. This will impart a rocking movement to plate 42 in imitating fleeting clouds and shadow effects on the glass front. The light from the one lamp 19 provides all the illumination necessary for the different parts and the relative position of the different parts will be so arranged that a single lamp will do for all and this is one of the features of this invention.

All of the mechanism will be so timed as to move at different speeds with reference to each other in producing the necessary combination effect.

I do not limit myself to the precise means shown but may make such changes as to produce effects in accordance with the different kinds of business to be advertised and the particular effect to be produced in connection therewith.

It will be understood that the landscape scenery shown on the glass front, other than the waterfall feature, is painted or otherwise placed thereon and may be changed from time to time.

Having thus described my invention what I claim is—

35 1. In a device of the class described, a transparent front having stationary landscape scenery shown thereon, a frame in

which said front is secured, a back casing removably attached to said frame and providing a chamber in which the actuating mechanism is located, a partition with a slot, an illuminating lamp loosely inserted in said slot, a motor, and the operative connections between said lamp and motor.

2. In a device of the class described, the combination with a transparent front having stationary landscape scenery shown thereon, of a frame having a transparent display face set therein, a back casing secured to said frame, a partition having a slot opening therein and inserted in said casing, an incandescent lamp, a movement lever pivoted at one end and having the opposite end extending over said slot, the socket end of said lamp extending through said slot and engaging the free end of said lever, and the operative driving connections.

3. In a device of the class described, a glass front, a supporting frame inclosing the same, a back casing secured to said frame and having a chamber-space therein, a partition provided with a slot opening, a lamp movably positioned in said slot, a movement lever having a slotted end held in engagement with said lamp, a motor, a connecting rod, a motor and the operative connection between said motor and said movement lever.

In testimony whereof I affix my signature in the presence of two witnesses.

EDWARD J. BAKER.
